UNITED STATES PATENT OFFICE

ABRAHAM DROUTMAN, OF BROOKLYN, NEW YORK

HATBOX

Application filed September 12, 1928. Serial No. 305,405.

This invention relates to a hat box.

The object of the invention is the production of a box or container adapted to hold a lady's hat with other articles and protect them from injury by crushing, and maintain them clean and dry. The second object of the invention is the production of a box or container, which can be easily opened and which can be used as a traveling case. The third object of the invention is the production of a hat box, in which a hat can be securely and detachably located in place. The fourth object of the invention is the production of a container of which a portion can be detached to increase the carrying capacity thereof, when used as a traveling bag. The fifth object of the invention is the production of a dust proof box or container which can be easily opened.

In the accompanying drawings Fig. 1 represents a front elevation of an exemplification of the hat box or container in its closed position; Fig. 2 shows a section of Fig. 1 on the line 2, 2; Fig. 3 is an enlarged top view of a portion of Fig. 1; Fig. 4 indicates an enlarged fragmentary portion of Fig. 2 with some of the elements in a changed position; Fig. 5 represents a top plan view of the box or container in its open position; Fig. 6 shows an enlarged perspective view of a detail; Fig. 7 indicates a fragmentary elevation of the box or container with a modification and Fig. 8 shows an enlarged section of Fig. 7 on the line 8, 8.

The box or container in this exemplification is indicated to comprise the cup shaped body portion 20 preferably of metal, having the upper edge 21. The body portion 20 is fastened to the disc 22 preferably of metal, by solder or screws not shown. A plurality of latch springs 23, extend from the inner face of the cup-shaped body portion 20. The cup-shaped body portion 20 is preferably provided with a cover 25 of leather fastened to its outer surface and a lining 26 of fabric is fastened to its inner surface. The disc 22 is preferably provided with a cover 27 of leather.

Within the cup-shaped body portion 20 is detachably fastened the inverted cup-shaped

hat support 28, preferably of metal, having the crown 29, and the flange 30 extending from its lower edge. The said flange 30 is snapped below the latch springs 23 to hold it in place. A handle 31 of leather or fabric has its ends fastened to the crown 29. The outer face of the support 28 is provided with a cover 32 of fabric and the like.

A plurality of curved panels 36, preferably of metal, having tapering longitudinal side edges 37, lower edges 38, and curved peak ends 39, are hinged to the upper edge 21 of the body portion 20, by means of hinges. Each of said hinges comprises the member 40 having the end hinge portions 41 and 42 and the member 43 having the central hinge portion 44. The hinge portion 44 has extending therefrom the stop 45 and the hinge portion 41 has projecting therefrom the stop 46. A pin 47 connects the hinge portions of the hinge. The accompanying edges 48 and 49 of the hinge portions are adapted to bear against each other and function as stops, when the panels 36 are swung open to a predetermined angle.

Each of the panels 36 has fastened to its outer surface a cover 50 preferably of leather and to its inner face is fastened a cover 51 preferably of fabric. To the inner face of each of the panels 36 is connected a pocket 52 of fabric and the like with the upper open end 53.

At the upper end of one of the panels 36 is fastened the cup-shaped hood 55 by means of the rivets 56. A thimble 57 is fastened to the lower face of the hood 55, by means of solder or other means. The lower open end of said thimble is threaded for the nut 58. The crown of thimble is threaded for the screw 59 having the round head 60 at its lower end. The screw 59 extends through the threaded opening in the crown of the thimble 57 and the crown of the hood 55 and to its upper end is fastened the inverted cup-shaped cap 61. From the crown of the cap 61 extends the operating handle 62. The accompanying longitudinal edges of the panels 36 are provided with the well known separable fasteners 68 with the sliders 69 described in Patents Nos. 1,219,881, 1,243,458 and

1,302,606. The peak ends 38 of other panels 36 are adapted to bear on the outer face of the hood 55.

To the outer face of one of the panels 36 and somewhat below its peak end 39 is fastened a loop or ring 70, and to the other outer face of each of the other panels is fastened a hook or open ring 71. A strap or chain 75 extends through the rings 70 and 71 and its ends can be latched and locked, by means of the latch and lock 78. Hooks 79 extend from a pair of the rings 71 for the snap hooks 80 of the supporting strap 81.

Referring to Figs. 7 and 8 in place of the separable fasteners 68 the accompanying edges of the panels may overlap each other when in their closed position and fastened by the ordinary snap fasteners comprising the male members 85 and the female members 86.

To use the hat box or container, a hat may be located on the hat support 28, and the pockets 52 may be filled with various articles, or the hat support 28 may be removed by pulling the handle 81, until the flange 30 is disengaged from the latch springs 23. In the latter case the box or container provides a large space to have easily located therein clothing or other objects.

The hat box or container is then closed by first swinging up the panel 36 carrying the cup-shaped hood 55, and then the other panels 36 are swung up with their peak ends bearing on the hood 55. Next the user fastens the longitudinal edges of the panels 36 to each other by pulling up the sliders 69 on the separable fasteners 68, or engages the male members 85 and the female members 86 of the snap fasteners. By this means the curved peak ends 39 of the panels 36 are automatically seated on the cup-shaped hood 55. Next the user turns the operating handle 62, and thereby the cap 61 is lowered and pinches the said curved peak ends 39 between the cap 61 and the hood 55. By this means a waterproof and dust proof hat box or container is provided.

Various modifications may be made in the invention and the present exemplification is to be taken as illustrative and not limitative thereof.

Having described my invention what I desire to secure by Letters Patent and claim is:

1. In a container the combination of a body portion, panels having longitudinal edges, lower edges and peak ends, the lower edges of the panels hinged to said body portion in positions to locate the longitudinal edges of the panels adjacent to each other, fasteners along the adjacent edges of the panels, an element connected to the peak end of one of the panels and means to clamp the peak ends of the other panels to said element.

2. In a container the combination of a body portion, panels having tapering longitudinal

edges, lower edges and peak ends, the lower edges of the panels hinged to said body portion, means to detachably connect the longitudinal edges of the panels to each other, a cup-shaped hood connected to one of the panels at its peak end, a cap, a screw extending from said cap in threaded engagement with said cup-shaped hood and adapted to pinch the peak ends of the panels between said hood and cap.

3. In a container the combination of a body portion, panels having longitudinal edges, lower edges and peak ends, the lower edges of the panels hinged to said body portion, means to detachably connect the longitudinal edges of the panels to each other, a hood connected to one of the panels at its peak end and means to pinch the peak ends of the panels to said hood.

4. In a container the combination of a body portion, panels having longitudinal edges, lower edges and peak ends, the lower edges of the panels hinged to said body portion, means to detachably connect the longitudinal edges of the panels to each other, a hood connected to one of the panels at its peak end, a movable cap positioned over said hood, and means to position said cap to pinch the peak ends of the panels between it and said hood.

5. In a container the combination of a body portion, a hat support detachably connected within the said body portion, panels having longitudinal edges, lower edges and peak ends, the lower edges of the panels hinged to said body portion, means to detachably connect the longitudinal edges of the panels to each other, a hood connected to one of the panels at its peak end, a movable cap positioned over said hood, means to position said cap to pinch the peak end of the panels between it and said hood, and means to suspend the container extending from said panels.

Signed at the borough of Manhattan, city of New York, in the county of New York and State of New York, this 31st day of August, 1928.

ABRAHAM DROUTMAN.
